UNITED STATES PATENT OFFICE.

EVAN V. QUINN AND DELBERT GALLUP, OF OLEAN, NEW YORK.

RETORT-BOTTOM-BENDING DEVICE.

1,420,747.

Specification of Letters Patent. Patented June 27, 1922.

Application filed July 1, 1921. Serial No. 481,991.

To all whom it may concern:

Be it known that we, EVAN V. QUINN and DELBERT GALLUP, residing at Olean, county of Cattaraugus, State of New York, both 5 citizens of the United States, have invented certain new and useful Improvements in Retort-Bottom-Bending Devices, of which the following is a specification.

The bottoms of retorts used in the 10 destructive distillation of wood are flat and of sheet steel with the side edges slightly rounded up so as to form concavo-convex flanges and are oblong as such a retort of standard size is 52 feet long and 7 feet wide.

15 The bottom supports a pair of rails usually of standard gage upon which iron trucks loaded with wood are run, and the retort being sealed, heat is applied to the bottom. The steel bottom is softened by the heat especially when the retort is overfired. As 20 a result the great weight of the trucks and their loads causes the bottom of the retort to sag. Such sagging narrows the gage of the rails and also draws in the opposite sides

25 of the retort and reduces the clearance between the sides of the truck and the retort so that great damage results. Prior to our invention, the practice has been to place a

30 jack beneath the retort and thereby force the bottom upward, but such a procedure is objectionable first, because the arch usually employed beneath the retort must be torn out, and second, it does not effect the restoration of the retort sides to normal position.

35 The object of our invention is to provide means for restoring the retort bottom and sides to normal position and which will render unnecessary any disturbance of the usual arches beneath the retorts.

40 In the annexed drawings;

Fig. 1 is a vertical cross section of a retort illustrating the application of our invention thereto, some of the parts being shown in elevation, the parts being in the position 45 they occupy before the normal condition of the retort bottom and sides has been restored.

Fig. 2 is a side elevation of the jack.

Fig. 3 is a detail view of the connection 50 between the yoke and the spider.

At a suitable distance apart, lengthwise of the retort, say, by way of illustration, two feet, two holes, 10, are drilled through the retort bottom, 11, where sagging has occurred, through which, respectively, are passed two rods, 12, which also pass loosely

through holes, 13, in an oblong plate or spider, 14, on the under side of the retort bottom, and loosely through holes, 15, in a yoke, 16, above the retort bottom, and so 60 within the retort. Encircling the portion of the rod, 12, below the spider is a washer, 17, and extending into the washer hole around the rod is a split or two part cone, 18, the split being on a diametral line, and on each 65 half, or section, on its interior is a rib or tongue, 19, that enters an annular groove, 20, in the rod, so that when the cone is drawn into the washer and the latter pressed against the underside of the spider, the rods 70 and spider are securely held together so that upward pull exerted through the rods will pull the spider, and the adjacent portion of the retort bottom, upward. Yet, assembly and removal may be quickly and easily 75 accomplished; it being necessary simply to drop the rod far enough to free the cone from the washer to permit the cone to be applied to or removed from the rod.

Preferably, the upper portion of each rod 80 is threaded, and above the yoke a nut, 21, is screwed on the rod, a washer, 22, being interposed between the nut and the top side of the yoke.

At the center, or midway between the two 85 rods, the yoke has a hole through which passes a heavy rod, 23, that has a head, 24, on its lower end that bears against the yoke bottom. The upper portion of the rod 23, is threaded, and upon it is placed a heavy nut, 90 24, so supported during operation of the device, (as hereafter explained), as to cause, when rotated in one direction, the upward movement of the bolt, and with it the yoke spider, and sagged retort bottom. For revolving the nut, 24, it has beveled gear teeth, 25, cut upon its exterior with which mesh one or more, preferably two, diametrically opposite bevel pinions, 26, fixed each to a radially extending shaft, 27, 95 journaled in a thrust block or header, 28^a, lying between the nut and the spider and, of course, perforated for the passage of the bolt, 23. The projecting outer portion of the shaft, 27, is squared to receive a 100 ratchet wheel, 28 for engagement by a pawl, 29, on a lever, 30, mounted to rock freely on the shaft to revolve the ratchet wheel and thereby rotate the bevel pinion.

Pivoted to the thrust block and extending 110 downward and outward therefrom on each side is an arm, 31, which at the lower end is

2
attached at midlength to an elongated shoe, 32, that is adapted to engage the retort bottom at its side and thus exert a downward and outward pressure thereat simultaneously 5 with the upward pull on the retort bottom at its transverse center. Near each end the shoe is engaged by one end of a strut or brace bar, 33, that extends obliquely from the shoe to the side of the pressure-arm, 31, 10 near its upper end. Preferably, the struts are longitudinally adjustable, as by means of a turn buckle, 34, on each.

While we claim our mechanism specifically in connection with retort ovens, we also 15 contemplate the embodiment and application of our invention in such other relations as may present like conditions or others that will call for like application of force.

What we claim is:

20 1. The combination of a spider, a yoke, rods joining spider and yoke at separated points, a pull rod connected with the yoke, a pressure block through which the rod passes, means to exert pressure on said block simultaneously with a pull on said rod, and 25 oppositely situated, diverging thrust members.

2. The combination of a spider, a yoke, rods joining spider and yoke at separated 30 points, a pull rod connected with the yoke, a pressure block through which the rod

passes, means to exert pressure on said block simultaneously with a pull of said rod, and oppositely situated, diverging thrust members, each comprising an elongated shoe and 35 diverging struts reaching to the ends of the shoe.

3. The combination of a spider, a yoke, alining holes being provided in the spider and yoke, a rod passing through each set 40 of alining holes, a washer on each rod engaging the outer side of the spider, a split cone on the rod entering the washer hole, the cone sections and rod having interlocking engagement, means on each rod engaging 45 the outer side of the yoke, and pull and thrust members operatively connected with the yoke.

4. As a means for returning retort oven members to normal positions, an elongated 50 bearing member to engage the underside of the retort bottom, diverging thrust members to engage the top of the bottom towards opposite sides, and means within the retort that simultaneously exert an upward pull on said 55 bearing member and a downward and outward thrust on said thrust members.

In testimony whereof we hereunto affix our signatures.

EVAN V. QUINN.
DELBERT GALLUP.
